DESIGN FOR A CLOCK CASE

Max Schlenker, La Salle, Ill., assignor to Western
Clock Case Company, Peru, Ill., a corporation
of Illinois

Application June 29, 1934, Serial No. 52,384

Term of patent 7 years

To all whom it may concern:

Be it known that I, MAX SCHLENKER, a citizen of the United States, residing in the city of La Salle, in the county of La Salle and State of Illinois, have invented a new, original, and ornamental Design for Clock Cases, of which the following is a specification, reference being had to the accompanying drawing, forming a part thereof.

In the drawing:

Fig. 1 is a perspective view of a clock case showing my new design.

Figures 2 and 3 are respectively, front and side elevations of same, on a slightly reduced scale.

I claim:

The ornamental design for a clock case, as shown.

MAX SCHLENKER.

CERTIFICATE OF CORRECTION.

Design No. 93,523.

October 2, 1934.

MAX SCHLENKER.

It is hereby certified that the name of the assignee in the above numbered patent was erroneously described and specified as "Western Clock Case Company" whereas said name should have been described and specified as Western Clock Company, as shown by the records of assignments in this office; and that the said Letters Patent should be read with this correction therein that the same may conform to the record of the case in the Patent Office.

Signed and sealed this 13th day of November, A. D. 1934.

Leslie Frazer
